KNOTTER

Filed April 1, 1920

UNITED STATES PATENT OFFICE.

BURT A. PETERSON, OF ROCKFORD, ILLINOIS, ASSIGNEE, BY MESNE ASSIGNMENTS,
TO BARBER-COLEMAN COMPANY, OF ROCKFORD, ILLINOIS, A CORPORATION OF
ILLINOIS (1922).

KNOTTER.

Application filed April 1, 1920. Serial No. 370,396.

To all whom it may concern:

Be it known that I, BURT A. PETERSON, a citizen of the United States, residing at Rockford, in the county of Winnebago and

5 State of Illinois, have invented certain new and useful Improvements in Knotters, of which the following is a specification.

The invention has reference to devices used in the textile arts for uniting the ends 10 of thread or yarn, and while it relates more particularly to that class of tying device which is mounted upon the hand of an operative, the invention in some of its phases is not limited to use in this manner.

15 The general object of the invention is to provide a knot-tying implement which is of an advantageous character from a structural point of view as well as from an operative standpoint, reducing the cost of manufacture to a minimum consistent with a high 20 degree of efficiency in operation.

A more specific object of the invention is to provide a knotter having a smoothly and 25 easily operating actuating mechanism compactly arranged and enclosed within a small cylindrical casing rotatably mounted in a supporting frame, the whole being capable of support upon the hand of the operative in an advantageous manner permitting of a 30 substantially free use of the hand.

A further and important object of the invention is to provide an improved construction for the tying bill which renders the 35 same more rigid and durable and permits of the detachable mounting of the movable member of the bill in an improved manner.

In the accompanying drawings, wherein I have illustrated a preferred embodiment 40 of the invention, Fig. 1 is a fragmentary side elevation of my improved knotter. Fig. 2 is a vertical sectional view through the knotter taken substantially in the plane of line 2—2 of Fig. 3. Fig. 3 is a central vertical sectional view through the knotter 45 taken in the plane of line 3—3 of Fig. 2. Figs. 4 and 5 are vertical sectional views taken on lines 4—4 and 5—5 respectively of Fig. 3. Fig. 6 is a top plan view of the device with the tying bill shown in section. 50 Figs. 7, 8 and 9 are detail views showing

my improved construction for the tying bill.

The embodiment of the invention selected for purposes of illustration includes means whereby the knotter may be conveniently 55 mounted upon the hand of the operative.

Briefly, the knotter comprises a casing 10, cylindrical in form and rotatably mounted in a generally U-shaped frame 11 carried by a member 12. By means of this member, together with a strap (not shown), the device is mounted upon the hand of the operative. A tying bill 13 is rotatably supported by the casing through the medium of a spindle 14 journaled transversely thereof and having a gearing connection with an element 15 within the casing, the element 15 being fixed with reference to the frame 11. On the exterior of the casing adjacent the tying bill 13 is a thread clamping device 16 which is also fixed with reference to the frame 11 so that in the oscillation of the casing, the tying bill moves with reference to said device. The latter is operatively associated with the casing so that in the movements of the casing the device is actuated to clamp and hold the thread ends during the formation of the knot. The means for oscillating the casing comprises a thumb lever 17 made rigid with the casing, and a torsion spring 18, one end of which is made fast to the casing and the other end to the element 15 which is rigid with the frame 11. 75

The casing 10 is cylindrical in form and comprises a main or cup section 10^a having a cap portion 10^b detachably secured in position in any suitable way. Herein, said means comprises a bowed spring member 19 formed of wire and having its opposite ends bent outwardly so as to project through registering openings in the two overlapping portions of the casing. In the peripheral wall of the casing is provided a bearing 20 in which is journaled one end of the spindle 14, and diametrically opposite said bearing and secured within the casing is a member 21 providing a bearing for the opposite end of the spindle. Said member also has a socket 22 formed therein to provide a cam barrel for actuating the tying bill in a man- 100

ner well known in the art. Said tying bill is carried by the spindle 14 and projects through an opening 23 in the peripheral wall of the casing.

5 The frame 11 comprises side members 11^a and 11^b spaced apart sufficient to receive between them the casing 10, which is rotatably supported thereby, and is rigidly secured upon the member 12. Preferably the 10 upright portions of the frame are shaped to form guiding means for use in positioning the threads to be united in operative relation to the tying bill. Thus the member 11^a is shaped so that its forward edge extends beyond the periphery of the casing 11, and 15 said edge is rounded as at 24 (Fig. 1) to form the thread guide. The opposite member 11^b has its upper end projecting above the periphery of the casing and shaped to 20 provide a guiding edge 24^a which merges in a notch 25 forming a hook member 26 for receiving the threads to be united.

The tying bill 18, which is carried by the spindle 14, comprises a portion 27 fixed with 25 reference to the spindle and carrying a pivot pin 28 upon which is mounted a shearing and clamping jaw 29, and a stationary jaw or bill spring 30. The lower portion 30 of the jaw 29 is shaped to provide a cam wing 31 adapted to coact with the cam barrel 22 for operation thereby in the usual manner. As shown in Figs. 7 to 9 inclusive, the portion 27 of the tying bill is made integral with the spindle 14. This is accomplished by drilling the upper end of a piece 35 of drill stock to form a bore 32 and reducing the upper end portion of the bored stock by swaging, as shown at 33 (Fig. 8). The reduced end is then bent at substantially 40 right angles to the length of the spindle to form the portion 27, the formation of which is completed by cutting away one side of the reduced portion to reduce the thickness thereof by substantially one-half, 45 as shown in Fig. 9. The pivot pin 28 is then mounted in the proper position in the portion 27, which latter provides a sufficient quantity of metal to permit of a rigid mounting of the pin. This construction 50 substantially eliminates a difficulty which has been experienced in the past in mounting the pin with sufficient rigidity owing to the fact that in some prior constructions an insufficient amount of metal has been provided to afford a foundation for the pin. To provide retaining means for the lower 55 end of the bill spring while permitting of the detachable mounting of the same, the wall of the bore 32 upon diametrically opposite sides is shaped at 34 and 35 respectively (Fig. 9) so as to provide bearing surfaces for the opposite sides of the lower end of the spring, the portion 34 being adapted to force the upper end of the spring 60 into holding engagement with the movable

jaw 29. In the upper end of the bill spring is provided a suitable opening 36 for receiving the pin 28 and to insure that the bill spring shall not become disengaged from the pin, the latter is slightly elongated and the portion of the bill spring surrounding the pin is struck out as shown at 37 (Figs. 5 and 9).

The stationary element 15 comprises a stem 38 disposed coaxially of the casing 75 and a bracket portion 39 substantially circular in form and rigidly secured to the stem. The latter may be provided for this purpose with a flange 40 to which the bracket is rigidly secured. Upon the opposite ends of said stem are journalled the side walls of the casing 10, and the ends of the stem projecting through said walls are secured to the upright members 11^a and 11^b of the supporting frame 11 as by means of 80 screws 41 and 42. As shown in Fig. 1, one end of the stem 38 is of non-circular form and projects into a similarly-shaped opening in the member 11^a. In its central portion the stem is flattened and apertured as 85 at 43 so as to receive the spindle 14, the aperture being of sufficient size to permit of the relative oscillatory movement between the spindle and the stem. In order to secure the spindle in position in the casing, the screw 41 is provided on its free end with a stud 44 adapted to enter an annular groove 45 formed centrally of the spindle as 90 shown in Fig. 3. For the purpose of effecting a rotation of the spindle in the oscillatory movements of the casing, the spindle has formed at its lower end a pinion 46 which meshes with a gear segment 47 carried by the circular member 39 of the bracket 15 and preferably formed integral therewith.

The clamping device 16 comprises a pair of stationary members 48 and 49 and an intermediate member 50. Said members are mounted at their lower ends upon the stem 110 38 and the intermediate member depends below the members 48 and 49 and has secured thereon a roller stud 51. This stud is arranged to operate in a cam groove 52 (Fig. 4) provided in a member 53 which is 115 rigidly secured to the adjacent side wall of the casing. Preferably the members 48 and 49 are formed from a single sheet of metal connected by a web portion 54 (Fig. 4). The cam groove 52 is so shaped as to produce a longitudinal movement of the intermediate member 50 of the clamping device, and to permit of such movement relative to the stem 38, said member is provided with a central elongated opening 55. The upper ends of the members 48 and 49 are shaped to provide stationary jaws 56 while the upper end of the member 50 is shaped to provide a movable jaw 57. In order that the casing may oscillate with ref. 120 125 130

erence to the clamping device, it is provided in its peripheral wall with a slot 58 (Fig. 6); and to hold the clamping device stationary during the movement of the casing, the 5 circular member 39 of the element 15 is provided with an arcuate peripheral flange 59 which is notched as at 60 to neatly receive the clamping device. Said arcuate flange 59 also serves as a guard to close the 10 slot 58 irrespective of the position of the casing with reference to the clamping device.

The thumb lever 17, by means of which the casing is rotated in the operation of forming 15 the knot, has an arcuate base portion 61 (Fig. 5) which is rigidly secured to the peripheral wall of the casing, the lever being disposed in a convenient position for engagement by the thumb of the hand which carries 20 the knotter. The spring 18 which serves to restore the parts to their normal position is in the form of a torsion spring surrounding the stem 38, and having one end secured upon a pin 62 (Fig. 2) rigid with the stem and its 25 opposite end detachably connected with a tongue or finger 63 struck inwardly from the peripheral wall of the casing at the edge of the cup shaped section 10 thereof. The extent of movement of the casing by the operation 30 of the thumb lever 17 is limited by the engagement of said lever with the lower end of the frame 11; and to limit the return movement of the casing by the spring 18, a projection 64 is provided on the lower periphery of the casing. This projection is arranged to engage with a stationary stop 35 which is herein in the form of a flat spring member 65 carried by the hand holding member 12. This spring member, it will be seen, serves to cushion the impact of the projection and thus relieves the knotter of undue 40 shock and stress.

Briefly, the operation of the device is as follows: The two strands of thread to be 45 united are placed, with the aid of the guiding edges 24 and 24^a of the upright members of the supporting frame, in operative relation to the tying bill 13 and the clamping device 16. Relative movement is then effected 50 between the tying bill and the thread clamping device through the movement of the casing 10 by means of the thumb of the operative engaging the lever 17. In this swinging movement of the casing, the spindle 14 is swung with reference to the bracket 15 so that the pinion 46, meshing with the 55 stationary gear segment 47, rotates the spindle and hence the tying bill, the parts being relatively proportioned so that the tying bill rotates substantially through one and one-half revolutions. In such rotation of the tying bill, the loops of the knot to be formed are made while the threads are clamped by the clamping device 16. This clamping action 60 of the device 16 is accomplished by the

operative connection between the intermediate member 50 of the clamping device and the cam member 53 secured to the casing, the cam groove 52 being shaped to produce the clamping action upon the initial movement 70 of the casing 10. In the continued rotation of the tying bill 13, the threads are clamped thereby and then severed, and as the tying bill approaches the end of its stroke the loops are stripped therefrom while the ends 75 of the threads remain clamped so as to tighten the knot. Upon the release of the lever 17 by the operative the spring 18 restores the parts to their initial position.

It will be seen that I have produced a knot-tying implement of a very advantageous character. The construction is simple and the parts are very compactly arranged. Moreover, the actuating mechanism is wholly 80 enclosed and the relatively movable parts so mounted and arranged with reference to each other as to provide a smoothly operating mechanism of high efficiency.

The method of making the tying bill herein disclosed is claimed in my copending divisional application Serial No. 732,142 filed 90 August 15, 1924.

I claim as my invention:

1. A knotter comprising, in combination, a 95 stationary support, a casing rotatably mounted upon said support, a spindle journaled in the casing and having a tying bill projecting through one wall thereof, thread-guiding means carried by the support, thread-clamping means fixed with reference to the support and including a movable member operatively associated with the casing, and means for oscillating the casing and actuating said movable member.

2. A knotter comprising, in combination, a support comprising two upright spaced members, a casing rotatably mounted between said members, an element fixed with reference to the support and enclosed within the casing, a spindle journaled in the casing and having a gearing connection with said element, tying means operatively associated with the spindle, a thread-clamping device fixed with reference to said support and including a movable member operatively associated with the casing, and means for oscillating the casing.

3. A knotter comprising, in combination, a support having a pair of upright members spaced apart, a stem mounted at its opposite ends in said upright members, a casing journaled upon said stem, a spindle journaled in the casing and having knot-forming means operatively associated therewith, a member fixed to said stem and having a gearing connection with the spindle, a thread-clamping device including a member operatively associated with the casing, and means for oscillating the casing.

4. A knotter comprising, in combination,

- a supporting frame having two upright members spaced apart, a stem mounted at its opposite ends in said upright members, an annular casing entered between said members and journaled upon said stem, a spindle rotatably mounted in the casing so as to be swingable in the rotation thereof, said spindle having knot-forming means operatively associated therewith, thread-clamping means operatively associated with the casing, means for rotating the spindle in the swinging movements thereof, and means for oscillating the casing.
5. A knotter comprising, in combination, a supporting frame having two upright members spaced apart, an annular casing, a stem carried by said members and adapted to rotatably support the casing, thread-guiding and holding means fixed with reference to the support, and knot-forming means including a tying bill swingable with the casing and rotatable in the swinging movements of the casing.
6. A knotter comprising, in combination, a support having two upright members spaced apart, a stem mounted at its opposite ends in said members, a casing journaled on said stem, a spindle journaled in the casing, said stem having an enlarged aperture therefor receiving the spindle but permitting of relative oscillating movement therebetween, thread guiding and holding means fixed with reference to the support, knot-forming means carried by the spindle and means for effecting a rotation of the spindle as the casing moves with reference to the support.
7. A knotter comprising, in combination, a support including two upright members spaced apart, an annular casing rotatably mounted upon said members, an element fixed with reference to said members and enclosed within the casing, knot-tying means carried by the casing; a drive spindle for said means, a gearing connection between said spindle and said element, and thread guiding and holding means including a device operatively associated with the casing but fixed against swinging movement relative thereto.
8. A knotter comprising, in combination, a support including two upright members spaced apart, an annular casing rotatably mounted upon said members, an element fixed with reference to said members and enclosed within the casing, a spindle rotatably mounted in the casing and adapted to swing with reference thereto, knot-tying means carried by the spindle, means operatively associating said spindle with said element whereby in the swinging movements of the spindle rotation is imparted thereto, and a thread-clamping device fixed with reference to said element but having an operative connection with the casing whereby to clamp the threads being united when the casing is rotated to actuate the knot-tying means.
9. A knotter comprising, in combination, a support having two upright supporting members spaced apart, an annular casing rotatably mounted upon said members, knot-tying means including a tying bill rotatably mounted in the casing so as to be swingable in the rotation thereof, thread-guiding means fixed with reference to the support, means for actuating the tying bill in the rotation of the casing, and a thumb lever fixed upon the casing and projecting from the periphery thereof.
10. A knotter comprising, in combination, a support having two upright supporting members spaced apart, a casing rotatably mounted upon said members, knot-tying means including a tying bill rotatably mounted in the casing so as to be swingable in the rotation thereof, means for actuating the tying bill in the rotation of the casing, a thumb lever fixed upon the casing and projecting from the periphery thereof, and a torsion spring having one end fixed with reference to the support and the other end fixed with reference to the casing.
11. In a knotter, a cylindrical casing consisting of a main section and a cap, the main section having a peripheral wall and an end wall, means for detachably securing the cap to the main section, said cap and end wall having central bearing openings, a stem extending through said openings, a frame to which said stem is detachably secured, a tying bill carried by the casing, means connected to said stem for rotating the tying bill in the pivotal movement of the casing, a spring within the casing, one end of the spring being attached to the casing and the other end to the stem, and means for pivotally moving the casing against the action of the spring.
12. A knotter comprising, in combination, a stem, a casing rotatably mounted upon said stem, an element enclosed within the casing and fixed with reference to the stem, a thread-clamping device comprising a stationary member and a movable member, said device being fixed against swinging movement with reference to said element, and a tying bill carried by the casing and operable in the swinging movements thereof to coact with the thread clamping means to form a knot, said movable member of the clamping device having an operative connection with the casing so as to be operable in the rotation of the latter.
13. A knotter comprising, in combination, a supporting frame having two upright members spaced apart, a casing rotatably mounted between said members, an element fixed with reference to the support and

- wholly enclosed within the casing, a tying bill rotatably mounted in the casing and swingable in the oscillation of the casing, means operatively connecting the tying bill with said element whereby to effect a rotation of the tying bill in the swinging movements thereof, a thread clamping device fixed with reference to said element and operatively associated with the casing so as to be actuated in the movements of the latter, thread guiding members carried by said upright members, and means for rotating the casing.
14. A knotter comprising, in combination, a stationary support having two upright members spaced apart, an annular casing rotatably mounted between said members, knot-tying means including a tying bill carried by the casing, a thread-clamping device fixed with reference to the support, and actuating mechanism for said knot-tying means, said upright members of the support being shaped at their ends to form thread-guiding means.
15. A knotter comprising, in combination, a support having two upright members spaced apart, an annular casing rotatably mounted between said members, knot forming means including a tying bill carried by said casing, and thread guiding members formed integral with said upright members and projecting upwardly beyond the periphery of the casing in operative relation to the tying bill.
16. In a knotter, the combination of a spindle, and a tying bill carried by the spindle and comprising a portion formed integral with the spindle, a clamping and shearing member pivotally mounted upon said integral portion of the bill, and a bill spring detachably mounted on said stationary portion of the tying bill, the upper end of the spindle having a socket formed therein adapted to receive and hold the lower end of the bill spring.
17. In a knot-tying implement, the combination of a spindle, and a tying bill comprising a stationary portion rigid with the spindle, a pivot pin mounted in said stationary portion, a clamping and shearing member mounted on said pivot pin, and a bill spring also mounted on said pin, the upper end of the spindle having a longitudinal bore therein adapted to receive the lower end of the bill spring, and the walls of said bore being shaped to provide opposed bearing surfaces for the opposite sides of the bill spring.
18. In a knot-tying implement, the combination of a spindle having a tubular upper portion carrying a relatively flat upper end portion disposed substantially at one side of a line drawn diametrically across the upper end of the spindle, said flattened portion having a pivot pin mounted in its face sub-stantially centrally thereof, a thread clamping and shearing member mounted on said pivot pin, and a stationary jaw or bill spring also mounted on said pivot pin and having a portion depending into the upper tubular end of the spindle.
19. In a knot-tying implement, the combination of a spindle having a tubular upper portion carrying a relatively flat upper end portion disposed substantially at one side of a line drawn diametrically across the upper end of the spindle, said flattened portion having a pivot pin mounted in its face substantially centrally thereof, a thread clamping and shearing member mounted on said pivot pin, and a stationary jaw or bill spring also mounted on said pivot pin and having a portion depending into the upper tubular end of the spindle, said tubular end of the spindle being shaped upon opposite sides to provide opposed bearing surfaces adapted to releasably secure the lower end of the bill spring.
20. A knotter comprising, in combination, a casing, an element mounted within the casing, said casing and element being relatively rotatable, a spindle journaled at its ends in the casing and carrying a tying bill, said spindle having a gearing connection with said element, and a thread-clamping device stationary with relation to the element and having a movable member operatively associated with the casing so as to be actuated in the relative movements of the casing and the element.
21. A knotter comprising, in combination, a casing, an element wholly enclosed within the casing, a spindle journaled at its ends in the casing, a tying bill carried by the spindle, said spindle having a gearing connection with said element, thread guiding and holding means carried by said element but operatively associated with the casing, and means for oscillating the casing.
22. A knotter having, in combination, supporting means including a stem, a casing pivotally mounted upon said stem, a member secured to said stem within the casing, a knot tightener and stripper comprising a clamping element rigid with said member and a movable clamping element, said casing having a peripheral slot through which the knot tightener and stripper extends, and a flange on said member, said flange underlying the peripheral wall of the casing and serving to close the slot.
23. A knotter having, in combination, a frame, a casing pivotally supported in the frame, a member secured to the peripheral wall of the casing and extending inwardly, said member comprising a cam barrel and a bearing, said casing having a bearing diametrically opposite the first mentioned bearing, a spindle rotatably mounted in said bearings, a tying bill on said spindle, said

- tying bill comprising a movable jaw having a cam wing extending into said cam barrel, and means for oscillating the casing and rotating the spindle.
24. A knotter having, in combination, a pair of spaced supporting members, a stem rigidly attached to and extending between said members, a casing pivotally mounted on said stem, a gear segment enclosed within the casing and fixed with reference to the stem, a tying bill spindle carried by the casing, a pinion on said spindle meshing with said segment, said stem having a central aperture to accommodate the spindle, and means for oscillating the casing.
25. A knotter having, in combination, two spaced supporting members, a stem extending between said members, means for rigidly securing the stem to said supporting members, said means including a screw, a casing pivotally mounted upon said stem, a gear segment enclosed within the casing and fixed with reference to the stem, a tying bill spindle carried by the casing, a pinion on said spindle meshing with said segment, the spindle having an annular groove into which the inner end of said screw extends, and means for oscillating the casing.
26. A knotter comprising, in combination, a support, a casing rotatably mounted upon said support, knot-tying mechanism operable in the oscillatory movements of the casing, means for oscillating the casing, a projection on the casing, and a yielding stop on the support arranged to be engaged by said projection to limit the movement of the casing in one direction.
27. A knotter comprising, in combination, a support, a casing rotatably mounted upon said support, knot-tying mechanism operable in the oscillatory movements of the casing, means for oscillating the casing, and yielding means for limiting the movements of the casing in one direction.
28. In a knotter, in combination, a supporting member, a stem, means for rigidly securing the stem to said supporting member, said means including a screw, a casing pivotally mounted upon said stem, and a tying bill spindle carried by the casing, the spindle having an annular groove into which the inner end of said screw extends.
29. A knotter having, in combination, a support, a casing pivotally mounted upon said support, a gear segment enclosed within the casing and fixed with relation to the support, a tying bill spindle carried by the casing, a pinion on said spindle meshing with said segment, the spindle having an annular groove, a member located axially of the casing and extending into the groove, and means for oscillating the casing.
30. A knotter comprising, in combination, a frame, a casing pivotally supported by the frame, one end wall of the casing having a cam slot, a clamping member stationary with relation to the frame, a movably mounted clamping member having a stud engaging the cam groove, said casing having a peripheral slot through which the clamping members project, and means for pivotingly moving the casing.
31. A knotter having, in combination, a U-shaped frame, a casing pivotally mounted in the frame, a tying bill carried by the casing, said frame comprising two side members one of which projects beyond the periphery of the casing into position to guide the threads into the tying bill, the other side member projecting beyond the periphery of the casing and having a thread-receiving notch and a thread-guiding edge leading to said notch, and a knot-tightening and stripping device carried by the frame at a point intermediate the tying bill and the first mentioned side member.
32. A knotter having, in combination, two side members, a casing pivotally mounted between the side members, a tying bill carried by the casing, one of the side members projecting beyond the periphery of the casing into position to guide threads into the tying bill, the other side member projecting beyond the periphery of the casing and having a thread-receiving notch and a thread-guiding edge leading to said notch.
33. A knotter comprising, in combination, a support providing a pair of spaced supporting members, a stem rigidly attached to and extending between said members, a casing pivotally mounted upon said stem, a gear segment enclosed within the casing and fixed with reference to the stem, a tying bill spindle carried by the casing, a pinion on said spindle meshing with said segment, and means for oscillating the casing.
34. A knotter having, in combination, an annular structure, a tying bill spindle extending diametrically of said structure, said spindle having a peripheral groove, and a member located axially of the structure and extending into said groove to hold the spindle against longitudinal movement.
35. A knot tying implement having, in combination, a tying bill, a closed casing, an element independent of and wholly enclosed within said casing, and means for operating the tying bill through relative oscillation of the casing and said element.
36. A knot-tying implement comprising, in combination, a casing having two opposed side walls fixed with respect to each other, and a peripheral wall; a knot-tying bill passing through the peripheral wall and projecting therefrom; a gear segment independent of the casing but wholly enclosed therein and operatively connected to the tying bill; and means for effecting relative oscillation of the casing and said segment.
37. A knot-tying implement having, in

combination, a closed casing, a tying bill projecting from said casing, a gear segment independent of and wholly enclosed within said casing and operatively connected to the 5 tying bill, a thread clamp also projecting from said casing, means for effecting relative oscillation of the casing and the seg-

ment, said means including a spring within the casing, and means within the casing for operating the thread clamp in the movement of one of said relatively moving parts. 10

In testimony whereof, I have hereunto set my hand.

BURT A. PETERSON.

Certificate of Correction.

It is hereby certified that the name of the assignee in Letters Patent No. 1,509,409, granted September 23, 1924, upon the application of Burt A. Peterson, of Rockford, Illinois, for an improvement in "Knotters," should have been written and printed as *Barber-Colman Company* instead of "Barber Colman Company," as shown by the records of assignments in this office; and that the said Letters Patent should be read with this correction therein that the same may conform to the record of the case in the Patent Office.

Signed and sealed this 4th day of November, A. D. 1924.

[SEAL.]

KARL FENNING,
Acting Commissioner of Patents.
